ELASTIC PILE FABRIC

Merwyn C. Teague, Ridgewood, N. J., and Thomas G. Hawley, Jr., Naugatuck, Conn., assignors to United States Rubber Company, New York, N. Y., a corporation of New Jersey

Application October 26, 1940, Serial No. 362,964

2 Claims. (Cl. 28—80)

Our invention relates to an improved elastic pile fabric having a rubber backing bonded to the base of the tufts and the back of the fabric to hold the tufts in the ground fabric and to give it additional elasticity.

The fabric may be made by the method described and claimed in our copending application Serial No. 186,132, filed January 21, 1938, of which this application is a continuation in part, and is particularly useful as an upholstery material because it can be stretched smoothly over spherical surfaces.

Rubber has been applied to the back of pile fabrics for the purpose of securing the tufts in the ground fabric and to render it impervious, but the present pile fabric has an advantage over the prior fabrics because the rubber backing serves the dual purpose of holding the tufts in the fabric and imparting additional elasticity to it. Due to the double function of the rubber backing our pile fabric may be stretched and contracted freely without permitting the tufts to become loose and fall or be easily pulled out of the ground fabric.

The invention will be further understood from the following description when read in connection with the accompanying drawing illustrating an elastic pile fabric embodying the invention, and a method and mechanism for making same.

In the drawing:

Fig. 1 is a diagrammatic side elevation of a form of mechanism for condensing fabric between two stretched belts;

Fig. 2 is a longitudinal sectional view through a piece of pile fabric before it is condensed;

Fig. 3 is a view similar to Fig. 2 showing an elastic pile fabric embodying this invention, which comprises the pile fabric after it has been condensed and secured to the rubber backing; and

Fig. 4 is a plan view of the back of the fabric shown in Fig. 3.

The elastic pile fabric E shown in Fig. 3 may be made with the construction disclosed in Fig. 1 of the drawing in which the pile fabric F in Fig. 2 to be made elastic is supplied from a roll 10. The back K of the fabric F is adhered to a stretched condensing belt 11, to be described, with a rubber-containing fluid which may take the form of a solvent rubber cement which does not soften when under heat of vulcanization to such an extent as to release the condensed condition of the fabric, or an aqueous dispersion of rubber such as rubber latex with or without com-

pounding and/or vulcanizing ingredients and in either a vulcanized or unvulcanized condition to a workable degree. Some of the solvent rubber cements of the class referred to above are those made from crude rubber without mastication and from reclaim rubber which contains combined sulphur. It is desirable to use a desolvating agent during the solvating step to provide a maximum rubber content and minimum solvent content. Rubber containing fluid as used herein shall include any consistency or viscosity of the rubber containing materials which may be sprayed, spread or applied by a pick-up roll or the like. The rubber fluid may be applied to the fabric or to the condensing belt, or to both, but it is deemed preferable to employ rubber latex to impart the desired elastic properties to the fabric, and to apply it to the fabric by means of a spray. In the construction shown in Fig. 1, the latex is applied to the upper face of the fabric by the nozzles L and L'.

The present invention as above stated contemplates using the adhesive action of the rubber coating to temporarily secure the fabric to the condensing belt. It is therefore important that the coating upon the fabric be in a tacky condition when the fabric reaches the condensing belt. This tacky condition may be secured by heating or drying the latex upon the fabric, or by coagulating the latex either by heating or spraying a coagulant thereupon by means of the nozzle C, or a heat sensitive latex may be used. The heating or partial coagulation of the latex may serve also to make it less fluid so as to prevent too deep penetration into the fabric and to prevent it from flowing together to close the apertures of the fabric. The spraying nozzles L, L' and C are preferably inclined to the fabric as shown so that the spray will not be forced through the fabric but will be deposited upon the upper face thereof. If desired the nozzles L, L' may be arranged at such an angle and the pressure behind the spray may be so controlled as is known in the art that a porous layer of rubber may be deposited upon the fabric.

The fabric F is condensed in the construction of Fig. 1 by introducing it between the stretched portions of two elastic belts 11 and 15 to be firmly held therebetween. In this construction, the inner belt 11 passes around a large drum 12 and at some distance therefrom around a smaller drum 13 and the latter drum may have cooperating therewith a pinch roll 14 to prevent the belt from slipping therebetween. The large drum 12 is positively driven and the small drum 13 is posi-

tively driven at a slower surface speed. The effect of this is to tension the lower run of the belt 11 and to permit the upper run of this belt to contract.

The outer belt 15 like the inner belt 11 passes around the large drum 12 and together serve to tightly grip the fabric F between the two belts. The outer belt is shown as passing around the spaced drums 16 and 17 and the upper drum 16 has cooperating therewith the pinch roll 18, and the lower drum 17 may be a free-running drum. The drum 16 is operated at a slower surface speed than the large drum 12 so that the lower run of this belt will be stretched and the upper run relaxed to approximately the same extent as those portions of the belt 11.

In the construction shown in Fig. 1 the rubber-containing fluid is deposited upon the back K of the fabric F which engages the inner belt 11 so that the fabric will adhere to this belt instead of to the outer belt 15. A pinch roll 18' may be employed to press the belts 11 and 15 firmly together against the drum 12 to cause the fabric F to be firmly secured to the belt 11 by its adhesive rubber coating. This pinch roll serves also to prevent slippage between the drum and belts at this point.

It will be apparent from the foregoing that when the rubber treated fabric F is introduced between the stretched lower runs of the belts 11 and 15 it will be strongly gripped between these belts as they pass around the drum 12, and that as these belts and the fabric approach the upper quadrant of the drum 12, in the construction shown, the belts will be permitted to contract gradually, with the result that the fabric therebetween will be condensed gradually. The rubber-containing fluid will cause the fabric to adhere more or less firmly to the belt 11, and the contraction of this belt will therefore serve first to condense the fabric and then to hold it in the condensed condition. The treated and condensed fabric may be conducted by the belt 11 past the drying or heating mechanism 19 which will cause the rubber to set or become sufficiently vulcanized to yieldingly hold the fabric condensed. The condensed fabric E may then be stripped off of the belt 11 and wound upon the roll 20, whereupon the rubber may be further vulcanized or otherwise treated. For example, two such fabrics may be plied together but in order to unite the two fabrics additional rubber adhesive should be introduced between them.

The construction shown in Fig. 1 utilizes the tension of an elastic belt to press the fabric against the drum and this serves to hold the fabric in a smooth flat condition while it is being condensed. The rubber-containing liquid on the fabric may if desired be partly dried or partly coagulated as it passes around the drum 12 by heating the drum. Care should be taken however, not to set the rubber by vulcanization before the fabric is condensed.

The elastic belts 11, and 15, may be formed of a porous or non-porous rubber sheet, or of a length of webbing, and the webbing if woven of elastic 65 warps and non-elastic wefts can be stretched longitudinally without contracting appreciably transversely. In condensing a woven fabric it is frequently important to use a belt the width of which does not vary appreciably as the belt is stretched. 70 longitudinally and then permitted to contract, for a woven fabric tends to pull away from a belt that expands transversely as it contracts lengthwise.

In some cases it may be desirable to produce a two-way stretch pile fabric. This may be done 75

by stretching the condensing belt both longitudinally and transversely before the fabric is adhered thereto, and then releasing the tension in both directions and condensing the fabric in both directions.

The elastic fabric made in accordance with the present invention comprises one or more condensed laminae of textile fabrics elastically bonded to a lamina of rubber. The term "textile fabrics" shall include only those fabrics which are composed of interconnected, or interlaced textile threads or yarns and which have an open construction so that the fabric may be condensed in accordance with the process herein described.

15 Loosely woven fabrics composed of such textile threads which may or may not contain bare or covered rubber threads, may be condensed in accordance with the present invention. When the textile fabric is condensed its thickness is increased to some extent and it is given a closer texture in appearance. The term "condensed" as applied to the textile fabrics shall mean that the fabrics are contracted in either their longitudinal, or transverse direction, or both of such directions 20 and to a greater extent than at the time the textile fabrics are adhered to the stretched condensing surface, and that the threads in such fabrics are relaxed in one or more of such directions to a greater extent than the threads in the 25 normal unstretched textile fabrics and the term "relaxed" as applied to the present invention shall be so construed. As compared to the normal finished condition of the textile fabrics used, the textile fabric lamina or laminae so condensed has 30 an additional stretch imparted to it in either the longitudinal or transverse direction, or both.

In Fig. 2 is shown in longitudinal section a piece of pile fabric which may constitute the fabric F before it has been condensed, and Fig. 3 is a similar view of such fabric after it has been condensed upon the apparatus shown in Fig. 1, or by other means. It will be noted that the pile tufts T are closer together in Fig. 3 than in Fig. 2 and that the ground fabric is held in a condensed condition in Fig. 3 by the rubber backing B so that it may stretch under tension. The rubber backing B is bonded to the condensed ground fabric G and to the base S of the tufts T, and normally retains the ground fabric in a condensed condition, but permits the fabric to stretch under tension. The rubber backing B also assists in holding the tufts in the ground fabric and prevents them from coming out when the fabric is stretched. The backing B may be made of solid rubber, or it may be made porous by any suitable method, such as by spraying the rubber-containing fluid on the fabric as previously referred to so as to produce the pores P.

Heretofore it was desirable to closely weave the ground fabric so as to hold the tufts in place. In accordance with the present invention it is desirable to use a relatively open weave in the ground fabric so that it can be condensed and rely upon the rubber backing B to retain the tufts in the ground fabric as it is stretched and contracted. This elastic pile fabric is particularly well adapted for use in upholstery work where it will conform more snugly to the surface being covered than non-elastic pile fabric, and will also stretch to relieve strains thereupon.

A loosely constructed pile fabric when treated in accordance with the present invention may be converted into an elastic fabric having a stretch considerably in excess of 100% of the stretch of the original fabric.

Whereas the elastic pile fabric illustrated herein has a woven ground fabric, it is to be understood that a knitted ground fabric may also be used. As various other modifications than those disclosed herein will occur to persons skilled in the art, it is not intended to limit the invention other than as required by the scope of the prior art and as set forth in the appended claims.

Having thus described our invention what we claim and desire to protect by Letters Patent is:

1. An elastic pile fabric comprising a lamina of rubber, a loosely constructed ground fabric, and tufts enmeshed with the threads of said ground fabric, said ground fabric being condensed in one direction so that its threads extending in said direction are relaxed when said rubber lamina is not under tension from any outside source, and said rubber lamina being elastically bonded to the bases of said tufts and to said ground fabric and retaining said relaxed threads of said ground fabric in such relaxed condition when said rubber lamina is not under tension from any outside

source, whereby said fabric is rendered elastic in said direction by virtue of the elasticity of said rubber.

2. An elastic pile fabric comprising a lamina of rubber, a loosely woven ground fabric, and tufts enmeshed with the threads of said ground fabric, said ground fabric being condensed in the longitudinal direction so that its threads extending in said direction are relaxed and the tufts are brought closer together when said rubber lamina is not under tension from any outside source, and said rubber lamina being porous and elastically bonded to the bases of said tufts and to said ground fabric and retaining said relaxed threads of said ground fabric in such relaxed condition when said rubber lamina is not under tension from any outside source, whereby said fabric is rendered elastic in said direction by virtue of the elasticity of said rubber.
